UNITED STATES PATENT OFFICE.

BENJAMIN W. KINCAID, OF WILSON, NORTH CAROLINA.

SEPARATOR.

991,212.

Specification of Letters Patent.

Patented May 2, 1911.

Application filed October 29, 1910. Serial No. 589,706.

To all whom it may concern:

Be it known that I, BENJAMIN W. KINCAID, a citizen of the United States, and a resident of Wilson, county of Wilson, and State of North Carolina, have made certain new and useful Improvements in Separators, of which the following is a specification.

My invention relates to improvements in separators and it is especially designed to be used with automobiles and gasoline engines for the purpose of separating the impurities in the liquid fuel from the fuel itself, thereby leaving the latter pure.

An object of my invention, as stated above, is to provide a device by means of which impurities, such as water, dirt, scale, etc., may be completely separated from the fuel fluid, such as gasoline, the said device having means for withdrawing the impurities after they are collected.

A further object of my invention is to provide a novel form of dirt separating means which consists of a receptacle for the dirt, and which may be cleaned by the pressure of the gasoline itself.

A further object of my invention is to provide a separator of very simple construction, and of few parts, and which is, therefore, cheap to manufacture.

Other objects and advantages will appear in the following specification and the novel features of the device will be particularly pointed out in the appended claims.

My invention is illustrated in the accompanying drawings in which—

Figure 1 is a central vertical section through the separator and through the main tank, and Fig. 2 is a detail view showing the sieves in the dirt receptacle.

In carrying out my invention, I provide a retainer such as that shown at 1 in Fig. 1. This retainer is of an elliptical shape in section, as shown in Fig. 1, and may be cast or otherwise made. At the bottom of the retainer is an opening 2, which is controlled by a stop cock 3. At the top of the retainer is an opening 4, which is normally closed by a screw plug 5, but which may be opened to permit the entrance of air. To ward the upper part of the receptacle is an outlet pipe 6, which may be controlled by a stop cock 7. This pipe leads to the carbureter. The dirt receptacle itself consists of a section of pipe 8. The pipe is provided on its upper side with a series of sieves 9, these sieves being of fine mesh, so as to

effectually prevent the dirt from passing through, but permitting the passage of water and gasoline. The pipe thus formed is passed through openings 10 and 11, respectively, and is secured therein by means of the nuts 12 and 13, which form parts of the packing glands 12^a & 13^a. Obviously, instead of using pack as glands, the pipe 8 may be soldered, brazed or otherwise secured in the walls without departing from the spirit of the invention. To the under side of the pipe 8 is screwed the connecting pipe 14, which leads to the main storage tank 15. A stop cock 16 is provided between the tank and the pipe 14. The end of the pipe 8 is closed by a screw plug 17 as clearly shown in the figures.

From the foregoing description of the various parts of the device, the operation thereof may be readily understood.

When the apparatus is set up, as described, the stop cocks 16 and 7 are opened. The fluid will pass down through the pipe 14 and into the pipe 8. The gasoline and water will pass through the sieves 9 which will screen out the dirt, and the latter, being heavier, will tend to fall down to the end of the pipe 8 as shown in the figure. The continual passage of the gasoline along the pipe 8 will tend to wash the dirt down toward the bottom end. The gasoline and water passing through the sieves will now enter the interior of the retainer 1 when the water, being heavier, will sink to the bottom. The lighter gasoline will pass on to the carbureter through the pipe 6 in a pure state, being freed from the water and the dirt, and as long as the engine is running the flow will continue, the water and the dirt being automatically separated from the gasoline.

When it is desired to clean the device the screw plug 17 is removed, when the pressure of the gasoline in the pipe 8 will force out the dirt and will clean the pipe 8 thoroughly. The plug 17 may then be replaced. The stop cocks 16 and 7 are now closed and the screw plug 5 is opened to admit air. The stop cock 3 is opened and the contents of the retainer are drained. The screw plug 5 and the stop cock 3 are again closed, and the stop cocks 16 and 7 are opened, whereupon the gasoline again flows in and the separator is ready for immediate use.

In actual practice, it will not be necessary to drain the apparatus very frequently, be-

cause it will take some time to fill up with dirt and water. It will be noticed that the dirt can not fall to the bottom and clog up the stock cock 3, but that the water is taken 5 out at one place and the dirt at another.

I claim:

1. The combination with a storage tank for liquids, of a separator comprising a retainer having an outlet opening at its top 10 and at its bottom, means for closing the top outlet opening; an inclined pipe arranged to pass through the interior of the retainer, said pipe being provided with a series of sieves on its upper side, a screw plug in the 15 lower end of the pipe outside of the retainer for opening and closing the end of the pipe, a stop cock at the bottom of the retainer for draining the latter, and a screw plug carried

by said retainer at the top thereof for admitting air.

2. The combination with a storage tank for liquids, of a separator comprising a retainer having an outlet opening at its top 20 and at its bottom, means for closing the top outlet opening, an inclined pipe arranged to pass through the interior of the retainer, said pipe being provided with a series of sieves on its upper side and having means at its lower end for opening or closing the pipe, means for draining the receptacle, and 25 connections between said tank and the upper end of said inclined pipe.

BENJAMIN W. KINCAID.
